[57] CLAIM

The ornamental design for an equipment shelter and the like, as shown and described.

DESCRIPTION

FIG. 1 is a front elevational view of the design for equipment shelter and the like.

FIG. 2 is a side elevational view of the design of FIG. 1. The opposite side is identical.

FIG. 3 is a rear elevational view of the design of FIG. 1.

FIG. 4 is a top plan view of the design of FIG. 1.

FIG. 5 is a front elevational view of another embodiment of the design of FIG. 1. The rear is identical but without the door structure.

FIG. 6 is a side elevational view of the embodiment of FIG. 5. The opposite side is identical.

FIG. 7 is a top plan of the embodiment of FIG. 5.

FIG. 8 is a front elevational view of still another embodiment of the design of FIG. 1. The rear is identical but without the door structure.

FIG. 9 is a side elevational view of the embodiment of FIG. 8. The opposite side is identical and the top is of the same inventive concept as FIGS. 4 and 7.

FIG. 10 is a side elevational of yet another embodiment of the design of FIG. 1. The opposite side is identical and the front and rear are of the same inventive concept as the front and rear in FIGS. 1, 5 and 8 and the top is of the same inventive concept as FIGS. 4 and 7.
